[57] CLAIM

The ornamental design for a toy skunk animal figure or similar article, as shown.

DESCRIPTION

FIG. 1 is a front perspective view of a toy skunk animal figure or similar article showing my new design;

FIG. 2 is a top plan view thereof;

FIG. 3 is a side elevation, opposite side being a mirror image thereof;

FIG. 4 is a front elevation;

FIG. 5 is a rear elevation;

FIG. 6 is a bottom plan view thereof; and

FIG. 7 is a bottom plan of an alternative embodiment, the other views being the same as in FIGS. 1-5.
